BUILDING INSULATION AND METHOD OF APPLYING SAME

Original Filed July 30, 1928 2 Sheets-Sheet 2

UNITED STATES PATENT OFFICE

ROBERT G. HALLIWELL, OF WILMETTE, ILLINOIS, ASSIGNOR TO ARMSTRONG CORK COMPANY, OF LANCASTER, PENNSYLVANIA, A CORPORATION OF PENNSYLVANIA

BUILDING INSULATION AND METHOD OF APPLYING SAME

Application filed July 30, 1928, Serial No. 296,207. Renewed January 24, 1933.

The invention relates to an improved building insulation and method of applying the same and has for its primary object the provision of an improved construction and method of this character adapted and arranged to provide economical insulation for building which is highly efficient in use.

Another object of the invention is to provide an insulation for buildings especially adapted for use in conjunction with pitched or flat roofs which is capable of economical application to such roofs and highly efficient in use.

Another object of the invention is the provision of an improved method for applying such insulation to buildings.

Other objects will appear hereinafter.

The invention consists in the combinations and arrangements of parts and the method 29 of application hereinafter described and claimed.

The invention will be best understood by reference to the accompanying drawings forming a part of this specification and in which—

Fig. 1 is a perspective view illustrating a roof in course of construction and provided with insulation embodying the invention;

Fig. 2, a perspective view of a reinforcing 30 bar employed in the construction;

Fig. 3, a perspective view of a modified form of reinforcing bar;

Fig. 4, a top plan view, shown partially in section, of a portion of the roof illustrated in Fig. 1;

Fig. 5, a transverse section taken substantially on line 5—5 of Fig. 4;

Fig. 6, a transverse section taken substantially on line 6—6 of Fig. 4;

Fig. 7, a longitudinal section taken substantially on line 7—7 of Fig. 4;

Fig. 8, a view similar to Fig. 7 but showing the insulating blocks in final positions; and

Fig. 9, a detail view illustrating a slightly modified form of construction.

The preferred form of construction and method of applying the same comprises a frame consisting of two end bars 10 preferably of angle iron and connected together

by longitudinal bars 11 which are preferably T-bars as shown. The end bars 10 are provided in the ends of the vertical legs thereof with notches 12 and 13 thereby forming projecting supporting lugs 14 and 15 adapted and arranged to rest on the lower flange 16 of the I-beams 17 constituting the ordinary purlins of a roof construction.

The notch 12 is substantially twice the length as the notch 13, thereby forming the supporting lugs 14 substantially twice the length of the supporting lug 15, as shown. This arrangement is provided so as to permit of the ready removal of the supporting frame from between the purlins 17 after the insulating blocks have been applied thereto.

In use, the inner edge of the notch 13 is kept in contact with the corresponding flange 16, thereby withdrawing the inner end of the opposite notch 12 from contact with its corresponding flange 16, as shown in Figs. 1 and 5.

When it is desired to remove the supporting frame from between the purlins, all that is necessary is to shift the frame over toward the side of the lugs 14 until the lugs 15 disengage from the corresponding flange 16 whereupon the frame can be removed from below the purlins. This permits of the removal of the frame after the insulating blocks have been placed in position, said insulating blocks preventing removal of the frame upwardly between the purlins.

I also provide a supply of reinforcing bars or strips 18, preferably of brass, or other non-corrosive metal or material, for insertion between the insulating blocks. These reinforcing bars are provided with a plurality of transverse openings 19 for the reception of sharpened dowel pins 20.

In applying the insulating blocks to the roof purlins 17, one of the supporting frames 10—11 is inserted between said purlins, as indicated in Fig. 1, with the lugs 14 and 15 resting on the flanges 16, as shown. Then two of the insulating blocks 21 and 22 are placed in position on the supporting frame and between the purlins. If desired, the joints 23 between the ends of the blocks may

be sealed by waterproof cement applied before insertion of the blocks. Then one of the reinforcing bars 18 is placed adjacent the edges of the blocks 21 and 22 and dowel pins 20 forced by the hand through the openings 19 and partially into said blocks, as indicated in Fig. 7. After partial insertion of the dowel pins, the reinforcing bar 18 is withdrawn from contact with the blocks, thereby straightening up the dowels, should any of them have been placed in position crookedly, as indicated by the dotted lines in Fig. 4. Then a new set of blocks are arranged on the supporting frame and forced by the hands against the protruding ends of the dowel pins 20 until the dowels are completely embedded in the adjacent blocks and a tight joint is made as indicated. The insulating blocks 21 and 22 are usually of cork or material readily penetrated by the pins 20 so that this operation can be readily performed by the hands. If desired, waterproof cement may be applied to the bars 18 before application and thereby a perfectly sealed joint perfected.

As each joint between two sets of blocks is thus completed, the supporting frame 10-11 is moved outwardly along the flanges 16 to constitute a support for the next set of blocks as shown in Fig. 1. A new reinforcing bar 18 is then applied as before and a new joint made. Thus the process is continued until the entire space between that pair of purlins is closed by the insulating blocks, after which the supporting frame may be removed from below as explained above.

The space between each adjacent pair of purlins is similarly filled or sealed by the insulating blocks and then the roof covering 24 is applied in the usual way over the purlins 17, thus completing the roof construction. In this way the insulation may be quickly and economically applied and a strong and durable construction provided. The reinforcing bars 18 are themselves reinforced by the stiffening effect of the insulating blocks on opposite sides thereof so that bars of relatively thin noncorrosive metal may be employed to hold the insulating blocks in place.

It will also be noted that the bars 18 are concealed between the insulating blocks and a smooth and attractive appearance thereby presented.

The specific form and arrangement of parts disclosed is a simple and effective one for the purpose.

In Fig. 3 of the drawings I have illustrated a modified form of reinforcing bar 18 in which sharpened tangs 25 are struck up from the bar and extended therefrom alternately in opposite directions, said sharpened tangs obviously serving the function of the dowel pins 20.

In the modified form of construction illustrated in Fig. 9, the steel purlins 17 are shown as covered by a concrete covering 26 having channels 27 in the opposite sides thereof. Here the process of application of the blocks 21 and 22 is substantially the same as before and after application of the blocks the necessary space 28 is preferably filled with waterproof cement thereby forming a completely sealed insulation. 75

The insulation thus applied is usually made of cork blocks and serves the usual purpose of such insulation preventing sweating, conserving heat in winter and excluding heat in summer, and also producing the usual 80 acoustic effects.

While I have illustrated and described the preferred form of construction and method of procedure for carrying my invention into effect, this is capable of variation and modification without departing from the spirit of the invention. I, therefore, do not wish to be limited to the precise details set forth but desire to avail myself of such variations and modifications as fall within the scope of 90 the appended claims. 85

I claim:

1. The method of applying building insulation which consists in first arranging a plurality of blocks of insulating material 95 end to end; applying a perforated plate to the sides of said blocks; sticking pins through said plate and partially into said blocks; partially withdrawing said plate over said pins; applying other blocks to the ends of 100 said pins; and then forcing said sets of blocks together.

2. The method of applying building insulation which consists in first arranging and cementing together a plurality of blocks 105 of insulating material end to end; applying and cementing a perforated plate to the sides of said blocks; sticking pins through said plate and partially into said blocks; partially withdrawing said plate over said pins; applying cemented blocks to the other ends of 110 said pins; and then forcing said sets of blocks together.

3. A building insulation comprising elevated spaced supporting members, there being open space between and below said members; a plurality of insulating blocks of relatively soft penetratable material extending between said supporting members; a relatively thin, flat reinforcing bar imprisoned between and contacting with said blocks and spanning the joints between them; and penetrating members securing said bar to said blocks on opposite sides of the joints between the blocks whereby said bar supports 125 the weight of said blocks and said blocks reinforce said bar against lateral flexing. 115

4. A building insulation comprising elevated spaced supporting members, there being open space between and below said mem- 130

bers; a plurality of insulating blocks of relatively soft penetratable material extending between said supporting members; a relatively thin flat reinforcing bar imprisoned and contacting with said blocks and spanning the joints between them, there being perforations in said bar on opposite sides of the joints between said blocks; and penetrating dowel pins extending through said perforations and penetrating the blocks on both sides of said bar and on opposite sides of the joints between said blocks whereby said bar supports the weight of said blocks and said blocks reinforce said bar against lateral flexing.

5. A building insulation comprising elevated spaced supporting members, there being open space between and below said members; a plurality of insulating blocks of relatively soft penetratable material extending between said supporting members; a relatively thin flat reinforcing bar imprisoned and concealed between said blocks and spanning the joints between them, and penetrating sharpened tangs struck up from opposite sides of said bar and arranged to penetrate said blocks on both sides of the bar and on opposite sides of the joints between said blocks whereby said bar supports the weight of said blocks and said blocks reinforce said bar against lateral flexing.

6. In the method of applying building insulation, the steps consisting in applying a perforated plate to the exposed edge of a slab of insulating material, sticking pins through said plate and partially into said slab, partially withdrawing said plate over said pins, applying a slab of insulating material to the exposed ends of said pins and then forcing said slabs together.

7. A building insulation comprising elevated spaced supporting members, there being open space between and below said members; a plurality of insulating blocks of relatively soft penetratable material extending between said supporting members; a relatively thin flat reinforcing bar imprisoned between and contacting with said blocks, and penetrating members securing said bar to said blocks, whereby said bar supports the weight of said blocks and said blocks reinforce said bar against lateral flexing.

In witness that I claim the foregoing as my invention, I affix my signature this 27th day of July, 1928.

ROBERT G. HALLIWELL.
